(57) **CLAIM**

The ornamental design for a shoe sole, as shown and described.

DESCRIPTION

FIG. 1 is a perspective view of the shoe sole;
 FIG. 2 is another perspective view of the shoe sole; and,
 FIG. 3 is a plan view of the shoe sole.
 The broken lines depict portions of the shoe sole that form no part of the claimed design.
 A characteristic feature of the novel design resides in the word "ZETA" formed into the sole.
